Primary Examiner — John R Yeh(74) *Attorney, Agent, or Firm* — Grossman, Tucker, Perreault & Pfleger, PLLC(57) **CLAIM**

The ornamental design for a mop as shown and described.

DESCRIPTION

FIG. 1 is a front view of our new design for a mop;
FIG. 2 is a side view thereof;
FIG. 3 is a perspective view of the mop in an upright position;
FIG. 4 is a perspective view of the mop in a folded and extended position;
FIG. 5 is an enlarged view of the mop taken from the indication in FIG. 3.
FIG. 6 is an enlarged view of the bottom handle grip of the mop taken from the indication in FIG. 1.
FIG. 7 is an enlarged view of the bottom handle grip of the mop taken from the indication in FIG. 3;
FIG. 8 is a front view of the top handle grip of the mop taken from the indication in FIG. 1; and,
FIG. 9 is a front, top perspective view of the top handle grip taken from the indication in FIG. 3.
The broken lines shown in the drawings depict portions of the mop that form no part of the claimed design.

1 Claim, 9 Drawing Sheets(56)
